United States Patent Office

Des. 227,836
Patented July 24, 1973

227,836

TUBE DISPENSER

Arve W. Roiko, 5536 N. Lilac Drive,
Brooklyn Center, Minn. 55430

Filed Nov. 3, 1971, Ser. No. 195,539

Term of patent 14 years

Int. Cl. D6—06

U.S. Cl. D6—87

FIG. 1

FIG. 2

FIG. 3

FIG. 4

FIG. 5

FIG. 6

FIG. 1 is a front elevational view of a tube dispenser showing my new design;

FIG. 2 is a side elevational view thereof;

FIG. 3 is a sectional view taken along line 3—3 of FIG. 1;

FIG. 4 is a sectional view taken along line 4—4 of FIG. 1;

FIG. 5 is a sectional view taken along line 5—5 of FIG. 1; and

FIG. 6 is a top plan view thereof.

The broken line representation of a tube in FIG. 1 is for purposes of illustration only.

I claim:

The ornamental design for a tube dispenser, substantially as shown and described.
